GAME BOARD

Herta S. Klaudt, Woodstock, Ill.

Application January 27, 1954, Serial No. 28,700

Term of patent 14 years

(Cl. D34—5)

To all whom it may concern:

Be it known that I, Herta S. Klaudt, have invented a new, original, and ornamental Design for a Game Board, of which the following is a specification, reference being had to the accompanying drawing, forming a part hereof.

I claim:

The ornamental design for a game board, as shown.
